DESIGN FOR AN AIR CONDITIONING REGISTER OR SIMILAR ARTICLE

Charles Demuth, Jamaica, N. Y.

Application November 24, 1939, Serial No. 88,471

Term of patent 14 years

To all whom it may concern:

Be it known that I, Charles Demuth, a citizen of the United States of America, residing at 112-07 New York Boulevard, Jamaica, Long Island, in the county of Queens and State of New York, have invented a new, original, and ornamental Design for an Air Conditioning Register or Similar Article, of which the following is a specification, reference being had to the accompanying drawing, forming a part thereof.

Figure 1 is a perspective view of an air conditioning register or similar article, showing my new design.

Figure 2 is a top plan view thereof.

Figure 3 is a sectional view thereof on the line 3—3 of Figure 2.

I claim:

The ornamental design for an air conditioning register or similar article, as shown.

CHARLES DEMUTH.
